RAIL ANTICREEPER

Filed May 4, 1929

INVENTOR

UNITED STATES PATENT OFFICE

ADONIRAM J. COOK, OF WESTERLO, NEW YORK

RAIL ANTICREEPER

Application filed May 4, 1929. Serial No. 360,559.

As is well known by those engaged in railroad operation, the general causes of rail creeping are: the wave motion of the track under the alternate application and release of a rolling load; the application of the brake, especially when the wheels slide; curvature of the track when the velocity of the train is greater or less than the velocity for which the outer rail is elevated; and descending grades. 10 Rails creep also excessively on bridges.

The main object of my invention is the provision of a device which when several thereof are combined with track rails and cross ties will prevent the creeping or longitudinal movement of the rails relative to the ties under traffic. Its function is to hold the rail in a fixed position relative to the tie so the force which causes creeping will be transmitted through both the rail and tie to the track ballast. 20

The invention consists in a rail anti-creep device, or rail anchor, fashioned from a single piece of resilient or spring metal to such a shape that when driven onto a flange of a track rail the shank of the device will be twisted about its longitudinal axis between the ends thereof and the metal be subjected to a torsional strain or tension the reaction of which will hold the anchor in frictional contact with the upper and lower surfaces of a flange of the rail under all conditions of service. 30

The accompanying drawing illustrates an example of the embodiment of the invention, the same being constructed, and applied to the rail and tie, according to the best mode I have so far devised for the purpose or end in view.

40 Figure 1 is a top plan view of sections of a rail and tie, showing the improved anchor in operative position.

Figure 2 is an end view of Figure 1 in elevation.

45 Figure 3 is a view of the anchor in perspective.

Figure 4 shows one end of the shank.

Referring to the several Figures, 5 designates a track tie; 6, a track rail of common 50 construction; 16, the base flanges of the rail,

and 7 are the spikes which secure the rail to the tie.

The anchor is of a single piece of spring or resilient metal; 8 is the shank of the anchor. The end of the metallic bar is bent or forged on a relatively long curve at 17 so that the end surface thereof at 9 is oblique to the length of the shank. A locking seat 10 is formed by the removal of metal or forging, see Fig. 4. 60

At the opposite end of the shank a top jaw 14 is formed by bending the end of the bar at 13 through an arc of about 180 degrees and to a position slightly oblique to the length of the shank. The metal of the under part of the jaw is bifurcated or split and the metal displaced to form two flanges 15, 15 which are inclined so their under surfaces will frictionally contact with the inclined top surface of the flange 16 of the rail. 70

Beneath the jaw 14 the metal of the shank is offset, bent or forged sideways at 11 so the surface of the projecting metal will bear against the side of the tie, and it is also offset, bent or forged upwardly to form a bearing seat 12 projecting above the top surface of the shank. 75

It will be noted that the top surface of the seat does not match the under surface of the jaw 14, but is displaced and out of center, consequently when the anchor is driven on the flange of the rail the stresses twist the metal of the shank longitudinally of its axis and cause the flanges of the jaw to firmly grip the top inclined surface of the rail flange. 80 As the metal of the shank is resilient, the shank acts as a torsion spring under tension to hold the anchor immovable relative to the rail under all conditions of service. 85

The anchor is applied by passing the same beneath a rail, extending the jaw 14 over the rail flange, and driving the jaw crosswise of the rail till the bearing seat 10 engages the edge of the opposite flange of the rail. 90

From the foregoing description it is clear 95 that I have provided a one-piece rail anchor which is cheap in first cost, simple in construction, and efficient in operation when applied in connection with a rail and tie.

A plurality of the devices illustrated will 100

in use anchor the rails to the ties so they cannot move relative to the ties, and consequently the force or forces which cause creeping must be transmitted to several ties at the same time and at different points, thus distributing the energy so the rails and ties will not move relative to the track ballast.

What I claim is:

10. 1. An anti-creep device for rails comprising a bar of metal having a jaw adapted to frictionally engage the top surface of a track rail flange and a sidewise offset of the metal of the shank adapted to bear against the under surface of a rail flange and also against a track tie, the said offset extending beyond one side of the jaw, whereby the shank will be placed under longitudinal torsional stress when the device is driven onto the flange of a rail.
15. 2. The subject-matter of claim 1 wherein the said sidewise offset metal of the shank is also offset upwardly towards the jaw to form a seat or surface to engage the under surface of a rail flange.
20. 3. A metallic anti-creep device having at one end a locking seat, as 10, at the opposite end a jaw, and the metal of the shank below the jaw offset both sidewise and upwardly towards the jaw.
25. 4. The subject-matter of claim 3 wherein the said jaw is provided with flanges.
30. 5. The subject-matter of claim 3 wherein the end of the device provided with the locking seat is curved upwardly from the longitudinal axis of the shank.
35. In testimony whereof I affix my signature.
ADONIRAM J. COOK.
